UNITED STATES PATENT OFFICE.

CHARLES DANIELSON, OF CANNON FALLS, MINNESOTA.

IRONING-BOARD.

1,099,591.

Specification of Letters Patent.

Patented June 9, 1914.

Application filed January 7, 1914. Serial No. 810,735.

To all whom it may concern:

Be it known that I, CHARLES DANIELSON, citizen of the United States, residing at Cannon Falls, in the county of Goodhue and 5 State of Minnesota, have invented certain new and useful Improvements in Ironing-Boards; and I do hereby declare the following to be a full, clear, and exact description of the invention, such as will enable others 10 skilled in the art to which it appertains to make and use the same.

My invention has for its object to provide an improved ironing board and is in the nature of an improvement on my United 15 States Patent 1,073,404, issued of date September 16, 1913, and entitled "Ironing board."

To the above end, the invention consists of the novel devices and combinations of 20 devices hereinafter described and defined in the claims.

In the accompanying drawings, which illustrate the invention, like characters indicate like parts throughout the several 25 views.

Referring to the drawings: Figure 1 is a plan view of the improved ironing board, supported from the top of a kitchen table, some parts being indicated by the means of 30 dotted lines; Fig. 2 is a side elevation of the same, some parts being broken away; and Fig. 3 is a transverse section taken on the line $x^3 x^3$ of Fig. 2.

The numeral 1 indicates an ironing board 35 having secured to its end portion, pairs of laterally spaced short supporting legs, 2 and 3. The pair of legs, 2, project straight down from the ironing board 1, and are rigidly connected to a tie bar 4, rigidly secured to 40 said ironing board. The tie bar 4, also prevents warping of the board 1. The legs 3, are secured to the ironing board 1, for longitudinal adjustment, thereon by a clamping head 5. Said clamping head 5, is provided 45 with a pair of oppositely projecting trunnions 6, on which the upper ends of the legs 3 are pivotally mounted for swinging movement toward and from the legs 2. At their intermediate portions the legs 3, are rigidly 50 connected by a tie rod 7. Notches 8 and 9 are found in the lower inner end portions of the pairs of legs 2 and 3, respectively. These notches embrace opposite edges of the top 55 of a kitchen table, indicated as an entirety, by the character y . When in an operative

position, the legs 3 are set oblique, as best shown in Fig. 2.

The clamping head 5 is mounted for longitudinal sliding movements on the under side of the ironing board 1 and is provided 60 at its intermediate portion with a notch 10, through which works a guide rail 11, rigidly secured to the under side and longitudinal center of the ironing board 1. This rail 11 is channel shaped in cross section and is provided with a longitudinally extended slot 12, which extends substantially the full length of said rail and within which works the body portion of a thumb nut equipped clamping bolt 13. The head of this bolt works in the 70 channel of the guide rail 11 and its lower end extends through a perforation in the clamping head 5, as best shown in Fig. 3. Obviously by adjusting the thumb nut of the clamping bolt, the clamping head 5 may be 75 frictionally secured to the rail 11 in different longitudinal adjustments with respect thereto. This adjustment permits the oblique legs 3 to be set in different adjustments with respect to the legs 2 in order to 80 adapt the ironing board to tables of different sizes. The notched engagement of the clamping head 5 with the guide rail 11 holds said head against transverse or twisting movements with respect to said guide rail. 85

To prevent warping of the end of the ironing board 1 a transverse cleat 14 is rigidly secured by screws or otherwise to the ironing board 1 adjacent to the inner end of the rail 11. The weight of the ironing board 1 holds 90 the notched ends of the legs 2 and 3 engaged with opposite edges of the top of the table Y and, under increased pressure on the ironing board 1, the legs 3 tend to fold inward and upward, thereby drawing the opposing notched ends 8 and 9 of the legs 2 and 3 into tighter engagement with the top of the table Y . 95

To apply a skirt to the main ironing board 1, the front end thereof is elevated a distance 100 sufficient to carry the notched ends 9 of the legs 3 out of contact with the top of the table Y . In this position of the parts, the skirt may be slipped over the elevated end of the main ironing board 1. During the 105 application of the skirt to the ironing board 1, the legs 3 will fold, when engaged by the skirt, into close engagement with the main ironing board 1, thereby permitting the skirt to freely slip thereover. After the skirt 110

is past the legs 3, said legs 3 will drop, under the action of gravity, and with the lowering of the elevated end of the main ironing board, the notched ends 9 can be made to again embrace the adjacent edge of the top of the table Y.

What I claim is:

1. The combination, of an ironing board, two sets of legs for said ironing board having notched lower ends engageable with the opposite edges of the top of a table, a guide rail secured to said ironing board, a clamping head slidably mounted on said guide rail, and having an intermediate notch through which said guide rail works, and means for securing said clamping head to said rail in different longitudinal adjustments with respect thereto, one set of said legs being secured to said clamping head, for folding movements toward and from the other set of said legs, which are rigidly secured to said ironing board.

2. The combination, of an ironing board, two sets of legs for said ironing board having notched lower ends engageable with the opposite edges of the top of a table, a guide rail secured to said ironing board, a clamping head slidably mounted on said guide rail, and having a pair of oppositely projecting trunnions, and a thumb-nut-equipped clamping bolt for securing said clamping head in different longitudinal adjustments on said rail, one set of said legs being mounted on the trunnions of said clamping head, for folding movements toward and from the other set of said legs, which are rigidly secured to said ironing board.

In testimony whereof I affix my signature in presence of two witnesses.

CHARLES DANIELSON.

Witnesses:

T. R. JOHNSON,
EMIL J. HOLMES.
